UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

1,362,670.

Specification of Letters Patent. Patented Dec. 21, 1920.

Application filed May 27, 1920. Serial No. 384,715.

To all whom it may concern:

Be it known that I, CARL D. BROWN, a citizen of the United States, and resident of Hopedale, county of Worcester, State of Massachusetts, have invented an Improvement in Warp Stop Mechanisms for Looms, of which the following description, in connection with the accompanying drawing, is a specification, like characters on the drawing representing like parts.

This invention relates to improvements in warp stop mechanisms for looms of the general type disclosed in United States Letters Patent No. 885,130, granted April 21, 1908, to George B. Ambler, in which the shipper knock-off mechanism is actuated by the contact of a bunter upon the lay with a dog which is vibrated by a governor across the path of the lay under the control of a normally vibrating feeler which is adapted to be arrested by engagement of a detector released by the breaking of a warp thread.

The principal object of the invention is to provide an improved and simplified mechanism for actuating the knock-off.

A further object of the invention is to provide a knock-off actuating mechanism which can be readily applied to usual commercial looms, particularly of the type above identified.

Other objects and features of the invention will more fully appear from the following description and the accompanying drawing and will be pointed out in the annexed claims.

In the drawings:

Figure 1 is a side elevation of a sufficient portion of a loom to illustrate my invention as applied thereto.

Fig. 2 is an enlarged detail side elevation of the improved mechanism for actuating the knock-off, and,

Fig. 3 is a plan view of the mechanism illustrated in Fig. 2.

The loom to which the present invention is applied may be of the usual commercial type comprising loom sides 1, a lay 2, carried by swords 3 and actuated through a pitman 4 from a crank shaft 5 which is journaled in suitable bearings in the loom side. The loom is provided with any form of suitable shipper such as 6 mounted upon a bracket 7 and held, during the normal operation of the loom, in a suitable notch in the breast beam 8, or an extension thereof, from which it is

released by a knock-off, preferably in the form of a bell crank lever 9 which is actuated through the mechanism forming the subject matter of this invention which will hereinafter be more fully described.

The loom is provided with the usual harnesses 10 and 11 which engage the warps 12 and 13 to form the shed, said warps passing over lease rods 14 and 15 carried by a bracket 16 suitably supported upon the loom sides. Usual detectors, supported by the warps 12 and 13 between the lease rods 14 and 15, are mounted upon detector bars 17 and 18 and are adapted to drop when released by a broken warp thread into the path of a vibrating feeler 19 carried by a rock shaft 20 which is mounted in suitable brackets 21 carried by the loom sides.

The rock shaft 20 is vibrated through a yieldably mounted arm 22 which is connected by a link 23 to one end of a lever 24, the other end of which is held by a suitable spring in engagement with a cam 25 upon the usual cam shaft 26.

The rock shaft 20 is also provided with an arm 27 which is connected by an adjustable link 28 with the arm 29 of a rock shaft 30 which is mounted in a bracket 31 secured to the loom side and which has at its end a governor 32 which, through the vibration of the feeler, causes the oscillation of a dog 33 across the path of a bunter 34 which preferably is adjustably mounted upon a bracket 35 which desirably is adjustably secured to the lay.

The general construction and operation of the mechanism above described may be, and as illustrated herein is, the same in effect as that disclosed in the patent to Ambler above described. In the old construction, however, the dog is pivotally mounted upon one end of a lever which is fulcrumed at its other end upon a stationary stud and intermediate of its ends is connected by a link to the knock-off, the pivot for the dog being normally held substantially in axial alignment with the governor rock shaft.

The present invention is designed to simplify this construction by eliminating the lever through which the knock-off is actuated and to provide a device which may be readily substituted therefor in looms having a warp stop mechanism of this general type.

In the improved construction the dog 33 is provided with an elongated slot 36 which

embraces the governor shaft 30 so that the dog is capable of a pivotal and sliding movement upon said governor shaft. The governor, as illustrated herein, is of the usual pear shaped construction and provided with an elongated slot 37 which receives a stud 38 projecting from the side of the dog 33, the connection being such that the oscillation of the governor imparts a pivotal movement to the dog while the slot 37 is so constructed as to permit sliding movement of the dog upon the governor shaft 30.

10 The knock-off actuating member 39, which is connected at one end to an arm 40, of the knock-off, is provided at its other end with a head 41 which has in it an elongated slot 42 which embraces the governor shaft 30 so that the knock-off actuating member 39, like the dog 33, is pivotally and 15 slidably mounted upon the governor rock shaft. The head 41 of the knock off actuating member is located adjacent to the dog 33 and is provided with a transverse slot 43 which receives a pin 44 projecting laterally from the dog 33.

15 The pin and slot connection between the dog 33 and the head 41 of the knock-off actuating member 39, is such as to permit free pivotal movement of the dog 33 under the action of the governor 32, but to transmit 20 sliding movement of the dog to the knock-off actuating member when the dog 33 is engaged and moved longitudinally by the bunter 34 upon the lay.

25 In warp stop mechanisms heretofore constructed the end of the dog 33 is usually provided with a V-shaped recess which is adapted to be engaged by the complementary V-shaped end upon the bunter 34. In 30 some instances as when the drop wires are of a different width the action of the detectors is such as to arrest the dog in the position in which the V-shaped notch in the end of the dog will not lie directly in the 35 path of the V-shaped end of the bunter. The engagement, therefore, of the bunter with one of the walls of the notch in the end of the dog produces a strain upon the mechanism which actuates the dog.

40 Another feature of the present invention consists in providing the dog with a flat face 45 which presents a considerable area adapted to be engaged by the end of the bunter 34, flanges 46 and 47 however, being 45 provided at the edges of the end of the dog to prevent possibility of the dog slipping out of engagement with the bunter. The dog will thus coöperate with any width of drop wire.

45 In the operation of the loom the feeler 19 is vibrated transversely beneath the detectors which hang upon the warps, this vibration being imparted by the cam 25 through the lever 24, the link 23 and the 55 yielding arm 22 to the rock shaft 20 which

carries the feeler 19. The normal oscillatory movement of the rock shaft 20 vibrates the arm 27 which, acting through the link 28, vibrates the arm 29 of the governor rock shaft 30. The governor, therefore, which is 70 fixedly secured to the rock shaft 30 acts through the stud 38 to oscillate the dog across the path of the bunter 34, the movements being so timed that the end of the dog will be depressed below the path of the 75 bunter upon one beat-up of the lay and raised above the path of the bunter upon the next beat-up. During this normal movement the stud 44 upon the dog oscillates in the slot 43 of the knock-off actuating member 80 without imparting any movement thereto.

If at any time one of the detectors is released by the breakage of a warp thread, it will fall into the path of the feeler 19 and 85 arrest the vibration of the feeler and its rock shaft 20 thereby arresting the vibration of the arm 27 and consequently the arm 29 which actuates the governor shaft 30. This will position the dog in the path of the 90 bunter. When the bunter 34, therefore, during the rearward movement of the lay, engages the end of the dog 33 it will slide the same endwise upon the rock shaft and through the stud 34 will also act to slide the 95 knock-off actuating member longitudinally, thereby rocking the arm 40 of the knock-off and causing the knock-off 9 to release the shipper from its locking notch, thus causing a stoppage of the loom.

100 It will be understood that the embodiment of the invention disclosed herein is of an illustrative character and is not restrictive; that, whereas, the dog and the knock-off actuating member are illustrated as being pivotally and slidably mounted upon the rock shaft, other means may be provided for permitting the pivotal and sliding movement of the same, and that various modifications in construction and arrangement of 105 parts to adapt the invention to other types of mechanisms may be made within the meaning and scope of the following claims.

110 Having thus described my invention, what I claim as new and desire to secure by Letters Patent, is:

1. Loom stopping means comprising a bunter carried by the lay, a pivotal and slidably mounted dog in coöperative relation with said bunter, an oscillating governor, means connecting said governor to said dog acting normally to oscillate said dog out of the path of said bunter, means operable upon an abnormal functioning of the loom to arrest said governor to position said dog 125 in the path of said bunter and means operable by the sliding movement of said bunter to stop the loom.

2. Loom stopping means comprising a bunter carried by the lay, a pivotal and slid- 130

ably mounted dog in coöperative relation with said bunter, an oscillating governor, means connecting said governor to said dog acting normally to oscillate said dog out of 5 the path of said bunter, a slidably mounted member, means connecting said dog to said member permitting free oscillatory movement of said dog but transmitting the sliding movement of said dog to said member 10 and means operable by the sliding movement of said member to stop the loom.

3. Loom stopping means comprising a bunter carried by the lay, a pivotal and slidably mounted dog in coöperative relation with said bunter, an oscillating governor, means connecting said governor to said dog acting normally to oscillate said dog out of the path of said bunter but to permit 15 sliding movement of said dog, means for 20 arresting said governor to position said dog in the path of said bunter upon breakage of the yarn and means operable by the sliding movement of said dog when engaged by said bunter to stop the loom.

25 4. In a warp stop mechanism for looms comprising a lay having a bunter, a shipper, a knock-off therefor, a series of detectors maintained in inoperative position by intact warp threads, a vibrating feeler to engage 30 and be arrested by a released detector; a pivotally and slidably mounted dog, means operable by said vibrating feeler normally to oscillate said dog out of the path of said bunter, but to position said dog in the path 35 of the bunter upon the arrest of said feeler, and knock-off actuating means having a connection with said dog permitting free pivotal movement of said dog but transmitting the sliding movement of said dog to said 40 knock-off actuating means when the dog is engaged by said bunter.

5. In a warp stop mechanism for looms comprising a lay having a bunter, a shipper, a knock-off therefor, a series of detectors 45 maintained in inoperative position by intact warp threads, a vibrating feeler to engage and be arrested by a released detector; a pivotally and slidably mounted dog, a pivotally mounted governor and means 50 for oscillating the same from said vibrating feeler, means connecting said dog to said governor operable by the oscillation of said governor normally to move said dog out of the path of the bunter but to position said 55 dog in the path of the bunter upon arrest of said feeler, and knock-off actuating means having a connection with said dog permitting free pivotal movement of said dog but transmitting the sliding movement of said 60 dog to said knock-off actuating means when said dog is engaged by said bunter.

6. In a warp stop mechanism for looms

comprising a lay having a bunter, a shipper, a knock-off therefor, a series of detectors maintained in inoperative position by 65 intact warp threads, a vibrating feeler to engage and be arrested by a released detector, a rock shaft and means for oscillating the same from said vibrating feeler, a governor on said rock shaft, a dog pivotally 70 and slidably mounted on said rock shaft, means connecting said governor to said dog for oscillating said dog across the path of the bunter but permitting longitudinal movement of said dog when engaged by 75 said bunter, an actuator for said knock-off slidably mounted on said rock shaft having a connection to said dog operable to permit free pivotal movement of said dog but to transmit movement to said knock-off actuator 80 when said dog is engaged by said bunter.

7. In a warp stop mechanism for looms comprising a lay having a bunter, a shipper, a knock-off therefor, a series of detectors maintained in inoperative position by intact warp threads, a vibrating feeler to engage and be arrested by a released detector, a rock shaft and means for oscillating the same from said vibrating feeler, a 90 governor on said rock shaft, a dog pivotally and slidably mounted on said rock shaft having a pin and slot connection with said governor operable to transmit the oscillatory movement of said governor to said dog 95 but to permit relative sliding movement between said dog and said rock shaft, a knock-off actuator slidably mounted on said rock shaft and a pin and slot connection between said dog and said knock-off actuator permitting free pivotal movement of said dog but transmitting sliding movement of said dog to said knock-off actuating means when said dog is engaged by said bunter.

8. In a warp stop mechanism for looms 105 comprising a lay having a bunter, a shipper, a knock-off therefor, a series of detectors maintained in inoperative position by intact warp threads, a vibrating feeler to engage and be arrested by a released detector, a pivotally and slidably mounted dog having a flat bunter engaging face having flanges at its edges to prevent the bunter from slipping off of the dog, means operable by said vibrating feeler normally to oscillate said dog out of the path of said bunter but to position said dog in the path of said bunter upon arrest of said feeler and knock-off actuating means operable by the sliding movement of said dog when engaged by 110 115 said bunter.

In testimony whereof I have signed my name to this specification.

CARL D. BROWN.
